UNITED STATES PATENT OFFICE

2,461,195

GENERATOR MOUNTING

Walter Kenneth Bodger, South Glastonbury, Conn., assignor to United Aircraft Corporation, East Hartford, Conn., a corporation of Delaware

Application January 30, 1945, Serial No. 575,347

5 Claims. (Cl. 60—44)

1

This invention relates to the assembly of a number of gas generators around a central gas collector, particularly for use in aircraft power plants.

In the copending Kalitinsky application, Serial No. 531,303, now Patent No. 2,441,196, is shown a power plant installation in which a number of free-piston units, each functioning as a gas generator, are arranged around a central gas collector from which the gas discharges through a burner to a turbine. A feature of this invention is an arrangement by which the generators may be supported directly by the collector. Another feature is the separate support of groups of generators spaced lengthwise of the collector.

In the copending Thompson application, Serial No. 575,346, filed January 30, 1945, a power plant of this type is shown in which the gas collector is made rigid enough to act as a cantilever on which the generators may be mounted. A feature of this invention is a gas collector which, except for the bands where the generators are mounted, is relatively thin and is required to carry substantially no other load than the pressure load resulting from the gas within the collector.

Other objects and advantages will be apparent from the specification and claims, and from the accompanying drawings which illustrate an embodiment of the invention.

Fig. 1 is a side elevation of the power plant.

Fig. 2 is an end elevation of the generators and burner of Fig. 1.

Fig. 3 is a sectional view through one of the generators and showing its attachment to the gas collector.

Each unit 8, as shown in Fig. 3, includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeve in combination with stationary pistons 28 and 30 form air spring cylinders.

The piston assemblies are moved apart by the burning of fuel injected into engine cylinder 10 through one or more nozzles 32. Air compressed in the air spring cylinders on the power stroke returns the piston assemblies. The assemblies are always maintained at equal distances from the center of the engine cylinder by a linkage, not shown.

Intake manifold 42 which extends around the compressor and engine cylinders, conducts air to intake valves 44 in the heads of the compressor cylinders through which air alternately en-

2

ters opposite ends of the cylinders. The compressed air leaves the cylinders through discharge valves 46, also at opposite ends of the compressor cylinders and passes into a central scavenging chamber 48 and end chambers 50 and 52. These chambers may be interconnected by a scavenging manifold, not shown.

Compressed gas from the scavenging chambers enters engine ports 54 and 56 which are uncovered by pistons 12 and 14 at the end of the power stroke, thereby permitting air to be blown through the engine cylinder. Gas in the engine cylinders is discharged through exhaust ports 58 into exhaust manifold 60.

Exhaust gas from the generators is discharged into an exhaust collector 62 to which the exhaust manifolds 60 are connected. In the arrangement shown, the generators are arranged in groups of four, substantially uniformly spaced about the collector, the groups being longitudinally spaced from each other along the collector.

The exhaust collector may have a centrally located combustion chamber 64 in the form of a duct connected by a duct 65 to the inlet of a turbine 66. If the power plant is used for aircraft the turbine may be connected through gear reduction units 68 and 70 and shafts 72 and 74 to a shaft 76 on which a propeller system may be mounted.

Exhaust gas from the generators is discharged into an exhaust collector 62 to which the exhaust manifolds 60 are connected. In the arrangement shown, the generators are arranged in groups of four, substantially uniformly spaced about the collector, the groups being longitudinally spaced from each other along the collector.

The exhaust collector is surrounded by a scavenging collector 80 which receives the gas from the compressors of the free-piston units and delivers gas to the scavenging ports in the engine cylinders. The scavenging collector is relatively cool and is subject primarily to the pressure load of the scavenging gas.

For supporting the generators the scavenging collector 80 has flanges 82 to which are directly connected the mounting flanges 84 on the case 86 that surrounds the free-piston unit and within which case the several elements of the free-piston unit are supported. The end scavenging chambers 50 and 52 may be connected to mounting flanges 88 and 90 on the scavenging collector, and it will be noted that the flanges 88 and 90 are relatively thin so that they do not carry any appreciable load other than the pressure loading from the scavenging gas.

The scavenging collector is reinforced circumferentially at the point where the mounting flanges 82 are provided by being thicker as indicated at 92 in Fig. 1. This reinforcing may be integral with the collector or may include heavy circumferential ribbing. In either event, the reinforcement at this section is sufficient to sup-

port without distortion the individual generators with the entire weight of the generator carried by the reinforced section of the burner. The case 86 of the free-piston unit forms the load-carrying member and since it is directly connected to the flanges 82 each generator may be cantilevered to the reinforced section of the burner without additional external support.

The load of each of the groups of four generators may be carried in the power plant installation by means of rods 94 and 96 extending from a central rigid beam 98 to a mounting bracket 100 integral with the reinforced section of the scavenge collector.

By the arrangement shown, longitudinal expansion of the scavenge collector may occur without affecting the mounting of the generator, since the rods 94 and 96 are pivoted on a pin 102 on the support 98, and each rod is pivoted on a pin 104 in the bracket 100. The weight of each group of four burners is carried through the reinforced section of the scavenge collector so that the remainder of the collector may be made of a relatively thin material since it carries substantially only the pressure load of the scavenge gas. Furthermore, by reinforcing the scavenge collector so that the generator may be cantilevered directly to the reinforcing rings, all extraneous supporting structure for the generators may be eliminated, thereby materially reducing the weight of the supporting structure for the generator.

Since the generators are hung from the rods 94 and 96, and the rods are pivoted on support 98, expansion of the burner structure may occur without damage to the supporting structure. Each group of generators may move toward and away from each other without the necessity for special provision for expansion.

It is to be understood that the invention is not limited to the specific embodiment herein illustrated and described, but may be used in other ways without departure from its spirit as defined by the following claims.

I claim:

1. A power plant including a scavenge collector, an exhaust collector within the scavenge collector, a number of free piston units around the scavenge collector, each unit having a scavenge opening, and a surrounding flange adapted to be connected to the scavenge collector, and said unit having an exhaust pipe extending through the scavenge opening and connected to the exhaust collector, said scavenge collector having a reinforcing ring to which the flange is connected.

2. A power plant including a scavenge collector, an exhaust collector within the scavenge collector, a number of free piston units around the scavenge collector, each unit having a scavenge opening, and a surrounding flange adapted to be connected to the scavenge collector, and said unit having an exhaust pipe extending through the

scavenge opening and connected to the exhaust collector, said scavenge collector having a reinforcing ring to which the flange is connected, said ring being substantially the entire support for the generators.

3. A power plant including a scavenge collector, an exhaust collector within the scavenge collector, a number of free piston units around the scavenge collector, each unit having a scavenge opening, and a surrounding flange adapted to be connected to the scavenge collector, and said unit having an exhaust pipe extending through the scavenge opening and connected to the exhaust collector, said scavenge collector having a reinforcing ring to which the flange is connected, said ring being substantially the entire support for the generators, and means on said ring for attaching the ring to a supporting structure.

4. A power plant including a gas collector, a number of free-piston units arranged in groups around the collector, said groups being spaced longitudinally of the collector, a reinforcing ring around the collector centrally of each group of free-piston units on which the units of each group are cantilevered, and supporting means movable with respect to each other, and engaging the longitudinally spaced reinforcing rings for supporting the groups of generators.

5. A power plant including a gas collector, a number of free-piston units arranged in groups around the collector, said groups being spaced longitudinally of the collector, each unit having a case within which the elements of the unit are mounted, said case having a flange surrounding a gas discharging opening, a reinforcing ring around the collector centrally of each group of free-piston units on which the units of each group are cantilevered, and supporting means movable with respect to each other and engaging the longitudinally spaced reinforcing rings for supporting the groups of generators, each of said reinforcing rings having integral flanges to which the flanges on the units are directly connected.
